Primary Examiner — Darlington Ly*Assistant Examiner* — Giang Hoang Tran(74) *Attorney, Agent, or Firm* — Frost Brown Todd LLP(57) **CLAIM**

The ornamental design for a vehicle muffler, as shown and described.

DESCRIPTION

FIG. 1 is a top, rear and right side perspective view depicting a vehicle muffler;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof; and,

FIG. 7 is a right side elevation view thereof.

The broken lines in the drawings depict portions of the vehicle muffler that form no part of the claimed design.
